UNITED STATES PATENT OFFICE.

DOMENICO RONCONI, OF CHICAGO, ILLINOIS.

TOY.

1,132,796.

Specification of Letters Patent. Patented Mar. 23, 1915.

Application filed November 12, 1913. Serial No. 800,624.

To all whom it may concern:

Be it known that I, DOMENICO RONCONI, a subject of the King of Italy, residing at Chicago, in the county of Cook and State of Illinois, have invented a new and Improved Toy, of which the following is a specification.

My invention relates to certain new and useful improvements in toys, and the invention particularly has for its object to provide a toy in which there is included a game table, at each end of which a figure of a child is placed, and a third figure is located at one side of the table, the table being designed with a runway for a ball that is adapted to be projected from one end of the table to the other by the one hand of the end figures, suitable clock works and lever mechanism being provided to effect the desired action, whereby the ball will be projected, the third figure having a pivoted head and mechanism coöperative with the other figures' mechanisms for causing the head of the third figure to be turned in the direction of the movement of the ball at each "push" of the same.

In its more subordinate nature, the invention includes those novel details of construction, combination and arrangement of parts, all of which will be first fully described and then be specifically pointed out in the appended claims, reference being had to the accompanying drawing, in which:—

Figure 1 is a longitudinal section and part elevation illustrating the invention in use. Fig. 2 is a cross section on the line 2—2 of Fig. 1. Fig. 3 is a detail section on the line 3—3 of Fig. 2, looking in the direction of the arrow. Fig. 4 is a detail perspective view of the clock works mechanism showing the operating cam. Fig. 5 is a detail perspective view of the trip lever that coöperates with the cam and is connected with the figure arm operating link. Fig. 6 is a detail perspective view of the arm pivot construction with the parts disconnected. Fig. 7 is a detail perspective view showing the parts of Fig. 6 connected, and Fig. 8 is a detail sectional view through the pivoted head of the third figure.

In the drawing in which like numerals designate like parts in all the figures, 1 represents the table top which is dished from the sides toward the center and provided with a runway or groove 2 at the center, the ends of which runway are cupped as

at 3 to form stop recesses for the ball or projectile 39. The table top has the upwardly projecting flanges 4 to prevent the ball accidentally rolling off, and the top is mounted on suitable legs 5, formed preferably integrally with the vertical supporting plates 6, the ends of which are slotted, as at 7, to permit passage of the links 41 that connect to the arm operating levers 14. 60 8 designates the end figures, one of which is designed to represent a boy and the other preferably to represent a girl, both of which figures may be seated on chairs 9 and secured at 40 to the table. Each of the 70 figures 8 is provided with a pivoted arm 10, the construction of which is best indicated in Figs. 6 and 7, by reference to which it will be observed that the arm 10 is provided with notches 11 in which the bendable lugs 13, of the tubular pivot 12, are projected and adapted to be clipped over, as indicated in Fig. 7, the pivot 12 is preferably integrally formed with the lever 14 that connects to the link 41. 75

15 designates the trip levers that are suitably bent to position, and one end of which is pivoted at 16 to the respective links 41, while the other end is provided with an offset 24 to form a shoulder 26 and leave a 85 finger 25 to coöperate with the cam 21 later referred to.

17 designates the clock works mechanism which may be of any approved type, and the supporting casing of which is provided 90 with slots 18 through which the trip levers 15 project, and in which they have bearing.

19 designates the power spring, and 20 the driven shaft on which the cam 21, is mounted. The cam 21 is provided with two 95 steps 22 and 23 whereby two distinct impulses may be imparted to the levers 15 at each turn of the cam, one impulse quickly following the preceding one so that in the event that the first impulse is not sufficient 100 to project the ball, the second one will. It will be noted that the shoulder 26 bears on the periphery of the cam 21, while the finger 25 engages the side of the cam and thereby forms a guide. The respective trip levers 105 15 are connected by a spring 27 so that the shoulders 26 may be held in contact with the cam and each lever 15 is provided with an arm 28 that is fastened at 29, and has a finger 30 to engage the projection 31 that 110 is carried by the rod 32 which passes through the opening 33 in the body of the

third figure 38 and projects upwardly, as at 34, to form the vertical pivot for the head 36 to which it is secured at 35. The body 38 has a neck pocket 37 for the head 36.

5 In operation, the clock works motor is wound up in the usual manner and the ball 39 placed on the table. The ball when placed on the table will gravitate into the groove 2, it being understood of course that 10 it must be placed originally in one of the pockets 3. The operation of the motor causes the rotation of the cam 21 which forces the levers 15 alternately out to lower the hand 42 of the figure into close proximity to the table and behind the ball. As 15 soon as the cam 21 has turned sufficiently to bring the step 22 into alinement with a shoulder 26, the spring 27 will quickly draw the lever 15 into the step of the cam and 20 thereby impart an upward and forward movement with respect to the vertical to the hand which throws the ball out of the pocket 3 toward the opposite figure, a second impulse being given immediately following the 25 first one. The shoulder 26 is spring pressed into the step 23, thus the ball will be alternately projected from one end of the table to the other, or from one pocket 3 to the other. As this occurs the head 36 will be 30 turned correspondingly by reason of the finger 30 engaging the lever 31 and giving it a push over. The lever 31 is not connected to either of the fingers 30, and the head 36 turns freely with the rod 43, the rod 43 35 lying on the pivotal axes. When the cam releases the member 15 so that the spring 27 can act quickly, the finger 30 gives a quick push on the lever 31, which turns the head 36 on the pivotal axes 34, it being understood that the lever 31 is rigidly fixed to the member 32.

From the foregoing description taken in connection with the accompanying drawing, it is believed the complete construction, operation and advantages of the invention will 45 be clear to those skilled in the art.

What I claim is:—

1. In a toy, a table having longitudinal runway, a toy figure mounted at each end of 50 the table, each of said toy figures including a movable arm, a ball on the table adapted to be projected by the movable arms from one end toward the other, a motor mechanism, coöperative connections between said motor 55 mechanism and the figure arms for imparting timed motion to said arms to alternately push the ball from one end of the table toward the other, and a third figure located along the side of the table and having a 60 pivoted head, and a coöperative connection between said head and said first mentioned figure, operating mechanism for turning said head in the direction in which the ball is rolling.

65 2. In a toy, a table having longitudinal

runway, a toy figure mounted at each end of the table, each of said toy figures including a movable arm, a ball on the table adapted to be projected by the movable arms from one end toward the other, a motor mechanism, coöperative connections between said motor mechanism and the figure arms for imparting timed motion to said arms to alternately push the ball from one end of the table toward the other, said last named 70 means including a cam, levers engaging said cam and operatively connected with said arms, and a spring continuously tending to pull said levers toward said cam, said cam having steps to effect a quick release of said 75 levers under the action of said spring, and a third figure located along the side of the table and having a pivoted head, and a coöperative connection between said head and said first mentioned figure, operating mechanism for turning said head in the direction in which the ball is rolling.

3. In a toy of the class described, a table, a toy figure located at each end of the table, each of said toy figures including a pivoted arm, mechanism for alternately actuating the pivoted arms of the respective figures, a projectile on the table adapted to be pushed by contact with said arms from one end toward the other upon operation of the respective arms, and means for limiting the travel of said projectile to a rectilinear direction, said actuating mechanism including a clock works mechanism provided with a cam rotatable in a vertical plane, and connections between the arms of each of said figures and said cam, and a single spring for holding all of said connections in engagement with the cam.

4. In a toy of the class described, a table, a toy figure located at each end of the table, each of said toy figures including a pivoted arm, mechanism for alternately actuating the pivoted arms of the respective figures, a projectile on the table adapted to be pushed by contact with said arms from one end toward the other upon operation of the respective arms, and means for limiting the travel of said projectile to a rectilinear direction, said last named means comprising a groove in the table, said table having depressions or pockets adjacent to the ends of the groove in which said projectile is adapted to rest, said actuating mechanism including a clock works mechanism provided with a cam rotatable in a vertical plane, and connections between the arms of each of said figures and said cam, and a single spring for holding all of said connections in engagement with the cam.

5. In a toy of the class described, a table, a toy figure located at each end of the table, each of said toy figures including a pivoted arm, mechanism for alternately actuating the pivoted arms of the respective figures, a pro-

- jectile on the table adapted to be pushed from one end toward the other upon operation of the respective arms, and means for limiting the travel of said projectile to a rectilinear direction, and a third figure mounted adjacent to the table, said third figure including a rigid body having a neck pocket, and a head having a neck projected into said pocket, a pivot on which said head is mounted, and a connection between said head and the mechanism that operates said figure arms for turning said head toward one of said end figures or the other according to the direction of motion of said projectile.
6. In a toy of the class described, a table, a toy figure located at each end of the table, each of said toy figures including a pivoted arm, mechanism for alternately actuating the pivoted arms of the respective figures, a projectile on the table adapted to be pushed from one end toward the other upon opera-
- tion of the respective arms, and means for limiting the travel of said projectile to a rectilinear direction, said last named means comprising a groove in the table, said table 25 having depressions or pockets adjacent to the ends of the groove in which said projectile is adapted to rest, and a third figure mounted adjacent to the table, said third figure including a rigid body having a neck 30 pocket, and a head having a neck projecting into said pocket, a pivot on which said head is mounted, and a connection between said head and the mechanism that operates said figure arms for turning said head toward 35 one of said end figures or the other according to the direction of motion of said projectile.
